UNITED STATES PATENT OFFICE.

EDWARD H. ANGIER, OF FRAMINGHAM, MASSACHUSETTS.

MACHINE FOR REINFORCING PAPER AND OTHER MATERIAL.

1,338,164.

Specification of Letters Patent. Patented Apr. 27, 1920.

Application filed December 29, 1916. Serial No. 139,484.

To all whom it may concern:

Be it known that I, EDWARD H. ANGIER, a citizen of the United States, and a resident of Framingham, in the county of Middlesex and Commonwealth of Massachusetts, have invented an Improvement in Machines for Reinforcing Paper and other Material, of which the following description, in connection with the accompanying drawings, is a specification, like characters on the drawings representing like parts.

This invention relates to the art of reinforcing paper or other material and among other objects provides a simple and efficient mechanism for applying reinforcing threads transversely to the length of the paper and if desired, longitudinally thereof as well.

The character of the invention may be best understood by reference to the following description of the illustrative embodiment of the invention shown in the accompanying drawings, wherein:

Figure 1 is a side elevation of the mechanism;

Fig. 2 is an end elevation as seen from the left of Fig. 1;

Fig. 3 is a plan; and

Fig. 4 is a central longitudinal section of a portion of the mechanism parts being broken away.

Referring to Fig. 1 of the drawings, in the embodiment of the invention shown there is provided a frame 1 having upper and lower presser rolls 3 and 5 mounted thereon. A sheet of paper 7 is led past a series of guide rolls 9 and a smaller guide roll 11 to and between the presser rolls 3 and 5. A second sheet of paper 13 is led over a guide roll 15 between the lower presser roll 5 and a roll 17 mounted beneath the same and thence between the presser rolls 3 and 5. A vat 19 beneath the roll 17 contains liquid black asphaltum or other suitable adhesive. The roll 17 revolves through the vat and applies the adhesive to the sheet 13. The arrangement is such that the sheets of paper meet between the presser rolls with the adhesive layer between and securing the sheets together. The above-described parts may be of usual well-known construction and therefore need not be described more in detail herein.

I shall next describe the mechanism for applying the reinforcing threads to the paper. The mechanism here shown is mounted on a base 21, preferably U-shaped in form,

and having bearings receiving trunnions 23 of a standard 25. This standard may be rocked on its trunnions to different positions of adjustment and be held by screw bolts 27 and caps 29 which engage the bearings. To limit the adjustment of the standard, it may be provided with lugs 31 to engage shoulders 33 projecting from said base bearings.

For supplying the thread or other reinforcing material for reinforcing the paper, I here show a rotary creel comprising a disk plate 35 having spool-supporting spindles 37 projecting from one face thereof, said plate being mounted, as best shown in Fig. 4, on a hollow shaft 39 (in effect a hub for the plate 35) journaled on a sleeve 41 fast in boss 43 at the upper end of the standard 25. The hollow shaft may be confined against axial movement at one end by engagement with the end of said boss, and at the other end by a cap 45 threaded on the sleeve. To guide the thread conducted from the thread spools, a second disk plate 47 may be provided having suitable eyes 49 for receiving the threads. This disk is mounted fast on the hollow shaft and rotates therewith.

I shall next describe traversing mechanism for laying the threads transversely to the length of the paper sheets. For this purpose the threads may be led from the guide plate 47 through eyes 51 on a sprocket chain 53 trained over sprocket wheels 55 mounted at the ends of a bar 57 which extends longitudinally of the paper feed rolls and closely adjacent to the bite between them. The eyes on the chain are moved through a substantially elliptic path markedly oblate and relatively long as compared with creel 35. The threads are, therefore, guided approximately into the plane of the paper and laid out across the same. To support the bar and chain in this position, the former may be provided (see Fig. 4) with a boss 59 fast on a tubular arm 61 projecting into a sleeve 63 which rests upon the lower surface of the fixed sleeve 41 referred to and is welded or otherwise secured thereto.

I shall next describe a suitable train by which the creel 35 and sprocket chain 53 may be driven from a motor 65 here shown as mounted on a bracket 67 secured to the lower end of the standard 25 referred to. The rotor of the motor 65 (see Fig. 1) has a pinion 69 meshing with a gear 71 fast on a shaft 73 (see Fig. 4) journaled in bear-

ings in the standard. Also on this shaft is a pinion 75 meshing with a gear 77 fast on a shaft 79 directly above the shaft 73 and journaled in bearings on the standard. 5 The shaft 79 extends rearwardly from the standard and is supported by an L-shaped arm 81, best shown in Fig. 3, fast on said standard.

To rotate the creel from the shaft 79 the 10 latter is provided with a pinion 83, seen at the right of the standard in Fig. 1, meshing with a gear 85 fast on the hollow shaft 39 which carries said creel.

To drive the sprocket chain from the shaft 15 79 the latter is provided with a gear 87 splined thereon and meshing with a pinion 89 fast on the shaft 91 which is journaled in a bearing in the arm 81. This shaft as seen in Fig. 4 projects forwardly through the 20 tubular arm 61 and its forward end is journaled in the boss 59 of the sprocket chain supporting bar. A pinion 93 fast on the shaft 91 is located between the upper and lower runs in the sprocket chain and engages the former to drive said chain. 25

Thus it will be apparent the creel and sprocket chain may be driven by a very simple transmission mechanism in different orbital paths.

30 When the machine is operating to apply the reinforcing threads to the paper, the traversing chain should be located closely adjacent to the rolls in order that it may maintain the desirable positive guidance 35 and control over the threads. However, there is a limit to the closeness with which the traversing chain can be adjusted to said rolls and to provide further control over the threads, fingers 94 may be secured to the 40 sprocket chain at points corresponding to the thread guiding eyes 51 thereon. These fingers may extend so close to the bite between the rolls that there is no opportunity for the threads to be diverted from their 45 proper accurate positions on the paper. I may also provide guide bars 95 supported in sockets 96 on the side frames 1 (see Fig. 3) and defining between them a narrow thread receiving slot parallel to the bite of 50 the rolls. The bars 95 may be set in between the overhanging parts of the rolls and close to their line of contact. By this means the threads are held spread out in a plane and so delivered to the paper.

55 The sprocket chain preferably extends somewhat beyond the ends of the paper feed rolls and therefore the threads will be carried out beyond the width of the paper sheet in the course of their traverse. To insure proper location of the bights of the 60 thread relatively to the edges of the paper, the threads on reaching the edges may be engaged by guides 97, here shown as rods mounted on the side frames 1 and having 65 portions closely conforming to the surface.

of the rolls. The cusp or point of this portion will engage the thread and guide the bight which would otherwise project beyond the edge of the paper into parallelism therewith. The bights of successive threads 70 thus disposed may overlap and form a sort of selvage.

To facilitate insertion of the threads through the eyes of the sprocket chain and its fingers and to permit ready access to the 75 paper rolls and the adhesive containing vat, it is desirable to draw the traversing mechanism away from the rolls. The support of the traversing mechanism on the tubular arm 61 lends itself advantageously to this 80 purpose. The tubular arm may slide axially in the fixed sleeve 63. To shift the tube it may have a ring 101 (see Fig. 1) fast thereon, the ring being connected by a link 103 with a hand lever 105 pivoted at 85 its lower end on the motor bracket 67. This lever has a spring-pressed hand grip 107 pivoted thereto provided with a dog 109 for engagement with lock notches 111 in the curved arm 113 connected to the standard 90 25 and the bearing arm 81 referred to. The ring 101 may be connected by a yoke 115 with the hub of the gear 87 (Figs. 1 and 4).

When it is desired to adjust axially the 95 sprocket chain driving shaft and the tubular arm receiving the same to present the traversing chain to different fixed operative positions or to withdraw the same from operative position to facilitate threading thereof or for purposes of adjustment or 100 repair, the entire arm 61 and the mechanisms carried thereby may be moved longitudinally by means of the hand lever 105. It will be observed that the gear 87 slides along its shaft 79 with the pinion 89 and is 105 adapted to rotate the latter and drive the sprocket chain when the latter is in its different positions of adjustment.

In some cases, to furnish further access 110 to the paper feeding and coating mechanism, it may be desirable to further withdraw the traversing mechanism therefrom. To accomplish this, the standard holding screw bolts 27 may be loosened and the standard and the parts supported thereby 115 may be bodily tilted backward up from the vertical, lifting the bar 57 and its associated mechanisms upwardly clear of the rolls 3 and 5. The screw bolts may be then tightened to hold the mechanism in this position. Thus by an extremely simple adjustment 120 the entire mechanism may be quickly and easily moved out of the way of the paper feeding and coating devices.

In same cases it is desirable to apply longitudinal reinforcing threads to the sheets in addition to the transverse threads. To accomplish this, a creel may be placed at any suitable location at the rear of the traversing mechanism and threads 117 may 130

be led from spools thereon to the crescent-shaped space 119 (see Figs. 2 and 4) between the fixed sleeves 41 and 63. The threads pass through this space and emerge 5 from the forward end thereof, diverge outward and enter a series of guiding eyes 121 in the sprocket chain supporting bar.

In operation the longitudinal and traversing threads are conducted from their 10 supply spools and threaded through their guides as described. They are then manually introduced between the paper sheets of the bite between the presser rolls. The rotation of these rolls will readily draw 15 the threads therebetween and the driven sprocket chain will lay the transverse reinforcing threads accurately and effectively in their transverse runs. It will be apparent that the angle of these transverse threads to 20 the edge of the paper sheet may be varied by relating the speed of rotation of the presser rolls as desired.

The mechanism for applying the transverse and longitudinal threads is a separate 25 unit from the paper feeding and coating mechanism, and therefore may be readily applied to standard mechanisms now in use without alteration thereof.

It will be understood that while the mechanism 30 has provision for introducing longitudinal reinforcing threads to the sheets, in some cases it may be desired to omit such threads and apply merely the transverse reinforcing threads to the sheets.

35 Having described one embodiment illustrating the invention without limiting the same thereto, what I claim as new and desire to secure by Letters Patent is:

1. The combination with a creel for receiving 40 spools of thread, of an endless carrier having eyes for guiding the thread, from said spools and movable through an oblate, substantially elliptical path, and means to rotate said creel and carrier to lay the threads 45 transversely of a strip of paper or other material.

2. The combination with a support, of thread supply means rotatably mounted thereon, thread guiding means movable in 50 an orbital path, and means simultaneously to drive said thread supply means and guiding means in orbital paths of different form to lay the threads transversely of paper or other material.

55 3. The combination with thread supply means, of thread guiding means, and means differentially to drive said means in orbital paths.

4. The combination with a pair of rolls 60 for feeding paper or other material, of means to apply reinforcing thread transversely to said paper including means to move a thread supply in an orbital path, thread guiding means movable in a path oblate relatively to said first path, and driving 65

means for said thread supply and guiding means.

5. The combination with a pair of rolls 70 for feeding paper or other material, of a member extending beside the rolls and substantially parallel thereto, rotors journaled on said member, a carrier on said rotors having thread guides thereon, a standard, and an arm pivotally carried by said standard for supporting said member.

75 6. The combination with a pair of rolls for feeding paper or other material, of means for applying reinforcing thread traversely thereto including a member extending longitudinally of said rolls, a thread 80 traversing guide carried by said member, a standard, and an arm supporting said member from said standard having provision permitting adjustment of said member relatively to said rolls.

85 7. In a machine for reinforcing paper or other material, the combination with a standard, of a sleeve fast thereon, a creel journaled on said sleeve, an arm mounted in said sleeve having an elongated member fast 90 thereon, sprocket wheels mounted on said member, a sprocket chain on said wheels having guides for conducting threads from said creel, and means for driving said sprocket chain including a shaft journaled 95 in said arm and a sprocket wheel on said shaft coöperating with said chain.

100 8. In a machine for reinforcing paper or other material, the combination with a support, of a sleeve thereon, a creel journaled on said sleeve, an arm mounted in and projecting from said sleeve, a thread guiding belt carried by said arm, and means for simultaneously rotating said creel and driving 105 said belt.

110 9. In a machine of the class described, a base, a standard pivoted thereto for swinging movement, a shaft journaled in said standard for longitudinal adjustment transversely of the standard and thread traversing means at the extremity of the shaft.

115 10. In a machine of the class described, the combination with a support, a thread carrying member having a hub journaled thereon, an arm projecting through the hub, a thread traversing carrier on said arm having thread guides thereon and a shaft associated with said arm to drive the carrier.

120 11. In a machine of the class described, the combination with a support, a thread carrying member having a hub journaled thereon, an arm projecting through the hub, a thread traversing carrier on said arm having thread guides thereon and a shaft associated with said arm to drive the carrier, 125 said arm and shaft being longitudinally adjustable through the hub.

130 12. In a machine for reinforcing paper or the like, a standard having a hollow journal bearing, a creel having a hub mounted there-

- on, a shaft extending through the bearing and having thread traversing means at an extremity thereof, a shaft 79 on said standard and geared to the first mentioned shaft 5 and to the creel.
13. A machine for reinforcing paper or the like which includes a rotary creel and a thread guiding carrier movable in an oblate path characterized by having the members 10 about which the motions of the creel and carrier are developed nested one within the other.
14. In a machine for reinforcing paper or other material, the combination with a support, of telescoping shafts thereon, a creel carried by one of said shafts, and thread traversing means driven by the other shaft.
15. In a machine for reinforcing paper or other material, the combination with 20 telescoping shafts, of thread supply means carried on and rotated by one of said shafts, and thread traversing means driven by the other shaft.
16. In a machine for reinforcing paper or other material, the combination with a support, a shaft thereon, a hollow shaft surrounding the first, thread traversing means carried by the former, thread supply means carried by the latter and means for rotating 30 the shafts.
17. In a machine of the class described, a support, a shaft mounted thereon for longitudinal sliding movement, thread traversing means at the extremity of said shaft for operation thereby and means to drive the shaft comprising a pinion thereon, a shaft 79 on the standard and a gear splined to said latter shaft.
18. In a machine for reinforcing paper, a standard, a sleeve thereon, a shaft mounted in said sleeve and smaller than the same whereby a space is defined between the shaft and sleeve, thread supply means, thread traversing means carried by said shaft, and 45 means associated therewith for guiding longitudinal threads, the space referred to serving as fair-leader and guide for such threads.
19. In a machine for reinforcing paper, a standard, a sleeve thereon, a shaft mounted in said sleeve and smaller than the same whereby a space is defined between the shaft and sleeve, and a transverse bar on said shaft and endless carrier trained about said 55 bar having thread guiding means thereon and eyes in said bar to receive longitudinal threads, the space referred to serving as fair-leader and guide for such threads to said eyes.
20. In a machine of the class described, a support, an endless carrier trained thereabout and having thread guides, means for driving the same, and thread guiding fingers extending from each guide and converging 60 toward a common plane transverse to the orbit of said carrier.
21. In a machine of the class described, the combination of a pair of rolls, an endless carrier having thread guiding means thereon movable adjacent the bite of said 70 rolls, and guides presenting a thread receiving slot parallel to the bite of the rolls.
22. In a machine of the class described, the combination of a pair of rolls, a traversing mechanism having a thread guide movable laterally beyond said rolls, and lateral thread engaging means adjacent the ends of the rolls for guiding the bights of thread received from said traversing mechanism longitudinally to form a selvage. 75
23. A machine of the class described comprising a base, a standard mounted thereon to rotate in a vertical plane, means to hold said standard in different positions of adjustment on said base, and thread guiding 80 and traversing means carried by the standard.
24. A machine of the class described comprising a frame or standard, a shaft extending transversely thereof and mounted for 90 sliding movement therein, a thread traversing mechanism carried by said shaft, means to drive the same, and means for slidably moving the shaft.
25. A machine of the class described comprising a frame or standard, a shaft extending transversely thereof and mounted for 95 sliding movement therein, means to hold the same in different positions of adjustment, a thread traversing mechanism carried by said 100 shaft, and means to drive the same independently of the adjustment thereof.
26. In a machine of the class described, in combination, a pair of rolls, a rotary creel, and orbitally movable thread traversing means between said creel and rolls and adjustable longitudinally between the two. 105
27. Apparatus of the kind described, comprising mechanism for advancing continuously in parallel spaced apart relation a pair 110 of filaments and applying the same to a paper sheet, an endless thread laying device having provision for guiding a series of threads to lay them diagonally crosswise on said filaments, said device having portions 115 adjacent said filaments relatively close to the plane thereof, and intermediate portions engaged with a driving means and relatively farther from the plane of said filaments, and a uni-directional bobbin carrier 120 connected for movement in synchronism with said thread laying device and equipped to hold a battery of bobbins sufficient to supply said device.
28. Apparatus of the kind described, comprising mechanism for advancing continuously in parallel spaced apart relation a pair 125 of filaments and applying the same to a

paper sheet, an endless chain guided for orbital movement with respect to said filaments with portions adjacent said filaments relatively close to the plane thereof, and an intermediate portion farther away from the plane of said filaments, said chain equipped with thread guides throughout its length,

and a bobbin carrier connected for uni-directional movement in synchronism with said chain and equipped to hold a battery of bobs 10 bins for the purpose stated.

In testimony whereof, I have signed my name to this specification.

EDWARD H. ANGIER.
